(57) CLAIM

The ornamental design for a golf club head cover, as shown and described.

DESCRIPTION

FIG. 1 is a front right side perspective view of our new golf club head cover design;

FIG. 2 is a side view thereof;

FIG. 3 is a front view thereof;

FIG. 4 is a bottom view thereof;

FIG. 5 is a top view thereof; and,

FIG. 6 is a side view thereof.

The portion of the golf club head cover shown in phantom does not form any portion of the present invention.

1 Claim, 3 Drawing SheetsFIG. 1

FIG. 2

FIG. 3

FIG. 4

FIG. 5

FIG. 6
